ADOLPH POTDEVIN, OF GARDEN CITY, NEW YORK, ASSIGNOR TO POTDEVIN MACHINE COMPANY, OF BROOKLYN, NEW YORK, A CORPORATION OF NEW YORK

SHOPPING BAG

Application filed October 12, 1928. Serial No. 312,005.

This invention relates to shopping bags of the type wherein a cord is operatively connected with a satchel-bottom bag to afford therefor a carrying element including a pair 5 of handle loops.

An object of my invention is to provide, in a bag of the type referred to, a novel construction and arrangement of the carrying cord whereby the loops thereof can be uniformly positioned with facility at the top of the bag irrespective of the form or quantity 10 of the contents of the bag.

Another object of my invention is to provide a novel construction of the bottom members of the bag whereby efficient cord retaining means, integral with the bag members, are provided.

A simple and efficient form of embodiment 20 of the invention whereby the foregoing objects are attained is herein illustrated, the scope of the invention being defined in the claims.

In the drawings—

Figure 1 is a perspective view of a tubular bag blank wherein the bottom slits and fold lines are indicated.

Fig. 2 is a similar view showing the slitted and creased end supplied with paste and partially folded in the bottom forming operation.

Fig. 3 is a similar view showing the next succeeding step in the folding operation.

Fig. 4 is a similar view, partly in section, showing the next succeeding step in the folding operation preparatory to the application of the carrying cord to the bag.

Fig. 5 is a similar view, showing the carrying cord as applied to the bag preparatory to the step of fixedly and slidably securing the respective members of the cord to the bottom 40 of the bag.

Fig. 6 is a similar view, showing one of the members of the cord slidably secured to the bottom of the bag.

Fig. 7 is a view of the completed bag in open condition.

Fig. 8 is a longitudinal vertical section through the bottom of the bag.

Figs. 9 and 10 are details of the overlapping and fastened ends of the cord.

The bag herein illustrated comprises a front 11, a back 12, and a satchel bottom 13, which bottom when the bag is empty and collapsed is foldable against one side of the bag as usual. This bag is composed of a flat tubular 55 body of paper, or other suitable material, having at one end thereof pairs of parallel longitudinal slits 14 between which central flaps 15, 16 are formed. In the manufacture of the bag these flaps are held at their free 60 ends and pulled longitudinally of the body of the bag in opposite directions to each other, thus drawing the opposite end portions of the body into bottom folds 17 of general V formation, from which the flaps 15, 16 extend outwardly, as represented in Fig. 2. These flaps 65 are then folded one upon the other and secured together and to the bottom folds, suitably-disposed areas of paste 18 having been previously applied to the upper surfaces of 70 the flap 16 and the folds 17.

In Fig. 3 the flap 15 is shown as folded and secured to the underlying bottom folds, preparatory to the folding of the flap 16, and in Fig. 4 the latter flap is shown as folded to 75 complete the formation of the bag bottom.

According to a feature of my invention the outer flap 16 is transversely slitted to a suitable extent inward from its respective lateral edges, as at 19, to form a pair of supplemental 80 tongues 20, 21 which may be flexed toward and from the bag bottom when the main body of the flap 16 is folded and secured in place, it being noted that the paste is applied to the flap 16, as indicated at 22 Figs. 2 and 3, to 85 permit the flexing of the tongues. These tongues afford simple and efficient means for securing an endless carrying cord to the bottom of the bag as will presently appear.

The front and back of the bag blank are 90 extended at their upper ends, as at 23, and the extensions are inwardly folded and may be pasted to the front and back respectively, thus reinforcing the margins of the bag. These reinforced margins are provided with 95 corresponding pairs of spaced-apart perforations 24. The front and back are also provided with similar pairs of perforations 25 below the perforations 24, said perforations 25 being somewhat above the upper edge of 100

the bag bottom when the latter is folded flatwise against one side of the bag, as seen in Fig. 4.

A carrying cord 26 of suitable length is applied to the foregoing described bag as follows, reference being had more especially to Fig. 5. One end of the cord is passed into the interior of the bag through one of the lower perforations 25 on one side, say the back, of the bag. The cord is then drawn upward and the end passed to the exterior of the bag through the aligning upper perforation 24 at the top of the same side of the bag. The end of the cord is then passed into the interior of the bag through the adjacent upper perforation 24 in the same side of the bag, and the cord is drawn downward and the end passed to the exterior of the bag through the other lower perforation 25, in the same side of the bag. The cord is then drawn downward and around the bottom of the bag and upward. The end is then passed into the interior of the bag through one of the perforations 25 on the other side, say the front, of the bag, and is threaded through the remaining perforations of the latter in the same order as described with respect to the perforations in the back of the bag, whereupon the leading end of the cord meets the other or trailing end of the cord at the bottom of the bag and the two ends are fastened together, thus producing an endless carrying cord embodying two longitudinal suspension members on each side thereof, handle loops 27 at the tops of the respective sides, and spaced apart transverse supporting loops 28 at the bottom of the bag.

The overlapping ends 29 of the cord are fastened together, preferably by spaced-apart wire staples 30 applied thereto and clinched, as seen in Figs. 9 and 10. The connected ends are placed upon and transversely of the bottom of the bag in close relation to the tongue 20, which tongue, being coated on its underside with paste 31, (Fig. 6) is folded upon and pasted to such ends and the bottom fold 15, thereby fixedly securing the cord to the latter. The adjacent parallel member of the cord is located upon and transversely of the bottom of the bag in close relation to the tongue 21 and the latter is then folded over the cord and pasted to the bottom fold 15, only that portion of the tongue 21 in contact with the fold 15 being provided with paste, as indicated at 32, Fig. 5. Hence the cord is slidably secured to the bottom of the bag.

From the foregoing it will be seen that my invention provides a simple and handy shopping bag wherein the two spaced-apart supporting strands which extend transversely of the bottom of the bag are fixedly and slidably secured to the bottom, respectively, thus permitting the ready manipulation of the endless carrying cord to ensure the proper

relative position of the handle loops when the bag is in service, regardless of the form or quantity of the contents of the receptacle. Also that the means for securing the cord to the bag comprises supplemental tongues which are integral with the outer flap of the bag bottom and are economically formed during the paper bag making operation, thus enabling the bottom to be completely folded and pasted by machine, with the tongues free to be pasted down after the bottom of the bag has dried and the cord has been applied thereto.

It will also be seen that by the described formation and arrangement of the tongues in relation to the bottom flaps the two spaced supporting strands of the cord, when it is applied to the bag, extend across the respective overlapping flaps throughout the width of the bag bottom, thus contributing to the strength of the flaps and their paste connection from side to side of the bag.

I claim—

1. A shopping bag comprising side walls, a satchel bottom therefor, including overlapping sealing flaps whereof the outer flap is formed with spaced-apart flexible tongues, and a carrying cord looped at the upper end of the bag and extended through and longitudinally of the side walls and transversely of the bottom of the bag, the bottom strands of the cord being spaced-apart and interposed between the inner flap and the respective tongues of the outer flap, and the said tongues being fastened to the said inner flap in a manner to secure the cord to the bag bottom.

2. A shopping bag comprising side walls, a satchel bottom therefor, including overlapping sealing flaps whereof the outer flap is formed with spaced-apart flexible tongues, and an endless carrying cord looped at the upper end of the bag at the respective sides thereof and extended through and longitudinally of the side walls and transversely of the bottom of the bag, the bottom strands of the cord being spaced-apart and interposed between the inner flap and the respective tongues of the outer flap, one of said tongues being fastened to the adjacent strand and the inner flap, and the other tongue being fastened to the inner flap only and securing the adjacent strand slidably to the bag bottom.

3. A shopping bag comprising side walls, a satchel bottom therefor, including overlapping sealing flaps whereof the outer flap is formed with spaced-apart flexible tongues, and a carrying cord looped at the upper end of the bag at the respective sides thereof and extended through and longitudinally of the side walls and transversely of the bottom of the bag, the ends of the cords being overlapped and united, said united ends being fixedly secured by and between the inner flap and the adjacent tongue of the outer flap,

and a spaced portion of the cord being slidably secured by and between the inner flap and the other tongue.

4. A shopping bag comprising side walls having pairs of perforations therein, a satchel bottom, and an endless carrying cord looped at the upper end of the respective side walls of the bag and threaded through the perforations to extend longitudinally of the side walls and transversely of the bottom at spaced locations, said bottom including an outer flap having spaced apart integral tongues whereby said cord is fixedly secured to the bottom at one location and is slidably secured to the bottom at the other location.

Signed at the city of New York, in the county of Kings and State of New York, this 10th day of October A. D. 1928.

ADOLPH POTDEVIN.
